UNITED STATES PATENT OFFICE.

HARRY D. SIMMONS, OF TROY, NEW YORK, ASSIGNOR TO CLUETT, PEABODY & CO., INC.,
OF TROY, NEW YORK, A CORPORATION OF NEW YORK.

BUTTONHOLE GAUGE.

Application filed October 28, 1924. Serial No. 746,338.

To all whom it may concern:

Be it known that I, HARRY D. SIMMONS, a citizen of the United States of America, and resident of Troy, in the county of 5 Rensselaer and State of New York, have invented new and useful Improvements in Buttonhole Gauges, of which the following is a specification.

This invention relates to devices for positioning collars (or cuffs) on button-hole making machines so that the button-holes are made in the correct place for a given 10 style of collar.

Heretofore it has been necessary for large 15 collar manufacturing establishments to employ skilled gauge setters who go from one button-hole making machine to another adjusting them to accommodate collars of a style different from the style for which they 20 had previously been set. These gauge setters measure the collars to determine the correct position for the button-hole and manipulate certain devices on the machine accordingly before the operator can continue 25 the work. It will be evident that in factories employing a large number of such machines much time is lost in waiting for the gauge setter, thus adding considerably to the cost of production.

Objects of the invention are to enable unskilled operators to position soft collars properly with respect to the button-hole making mechanism in a simple and convenient manner; to provide an attachment 35 for button-hole making machines having adjustable positioning devices which may be readily manipulated; and to provide a new and improved positioning device having the features of construction and arrangement 40 hereinafter described.

For purposes of illustration the invention is shown in the accompanying drawings in which—

Fig. 1 is a top plan view of a device for 45 positioning soft collars with respect to button-hole making mechanism;

Fig. 2 is a side edge view of the device showing the relative position of the cutter and needle;

Fig. 3 is a section on the line 3—3 of Fig. 1;

Fig. 4 is a section on the line 4—4 of Fig. 1;

Fig. 5 is a section on the line 5—5 of Fig. 1; and

Fig. 6 is a section on the line 6—6 of Fig. 1.

As illustrated, a relatively thin, flat metallic plate A is provided with a plurality of holes 1 for the reception of screws, bolts or other suitable fastening devices for connecting the plate to the carriage of a button-hole making machine, such as used in making button-holes in collars. As usually constructed the carriage of such machines 60 is propelled in accordance with the outline of the button-hole desired, the travel being with relation to a needle 2 which stitches the outline of the button-hole and thereafter a cutter 3 is actuated to cut the hole. 65 It will be evident that the collars must be carefully positioned on the plate A or the button-holes will be improperly positioned and as a result the collars will be rendered 70 useless.

In practice the collars are laid out flat on the plate A, a collar being indicated at B positioned over an opening 4 of substantial size in the plate which permits movement of the machine carriage without interfering with the stitching and cutting mechanism. For properly positioning the collars B on the plate A stops are provided against which the collars are moved so that when in such position the operator knows 75 definitely that the collars are accurately positioned for the button-hole making operation.

Ordinarily two plates A are provided for positioning the collars, the stops in the plate 80 serving to position a collar for making a button-hole at one end, and the stops on the other plate serving to position the collar for making a button-hole at the other end. In accordance with the invention 85 these stops are readily and conveniently adjustable so that an unskilled operator can adjust the machine for various styles of collars with a minimum amount of trouble and expenditure of time as will hereinafter be 90 described.

The stops for positioning the end of the collar B comprises a narrow plate or arm 5 which rests upon the upper surface of the plate A and is provided with a finger 6 100 fixed thereto having an upturned projection

7 which is adapted to be engaged by the notch in the collar B formed between the wing or fold and the collar band. Thus when the collar B is moved to engage the 5 projection 7 after the manner described the band of the collar is positioned with respect to the stitching and cutting mechanism of the machine. The stop 7 is adjustable to vary the position of the button-hole 10 crosswise of the collar band as well as longitudinally thereof to accommodate collars of different styles and sizes.

For adjusting the position of the stop 7, the narrow plate 5 is adjustably connected 15 to a substantially L-shaped arm 9, which is formed with a pair of parallel, rectangular elongate slots 10 and 11, a projection 12 on the under surface of the plate 5 being guided in the slot 10. A plate 13 is formed with a 20 similar projection extending into the slot 11 and is clamped to the arm 9 and plate 5 by screws 14. Thus it will be observed that by loosening the screws 14 the plate 5 may be adjusted in one direction or the other to 25 move the stop 7 crosswise with respect to the plate A, thereby positioning the collar B, relative to the longitudinal margins of its band and the stitching and cutting mechanism.

30 The stop 7 is further adjustable at right angles to the adjustment above described in order to adjust the position of the collar longitudinally, with respect to the stitching and cutting mechanism, thus accurately to position 35 the button hole lengthwise of the collar. Accordingly plates 15 and 16 are clamped as by screws to the opposite faces of the arm 9 and project over the plate A, a projection 17 on the upper face of the plate 16 extending into an elongate guide slot 18 in the plate A and a screw 17' holding the projection 17 in the slot. The opposite end of the arm 9 extends over the plate A, a plate 19 being secured as by screws to the plate A 40 and having an elongate slot 20 through which extends a screw 21 for fastening the arm to the plate 19. Thus by loosening the screws 17 and 21 the arm 9 may be adjusted to change the position of the stop 7 longitudinally with respect to the collar B.

To adjust the location of the collar B angularly with respect to the cutting and stitching mechanism thus to vary the angular position of the button-hole relative to the 55 longitudinal margins of the collar band, a stop 8 in the form of an upwardly projecting pin is fixed to a plate 22 which is formed with an integral projection 23 extending into an elongate guide slot 24, a plate 25 on the under side of the plate A being clamped to the plate 22 as by screws 26. By loosening the screws 26 the stop 8 may be moved in one direction or the other so that when the stops 7 and 8 are properly adjusted for a 60 given style a collar may be readily posi-

tioned on the plate A against the stops accurately for making a button-hole.

To enable unskilled operators to adjust the stops properly for different styles and sizes of collars the various adjustments are 70 preferably lettered D, L and S; D indicating the adjustment of the stop 7 crosswise with respect to the collar, L indicating the adjustment of the stop 7 longitudinally, and S indicating the adjustment of the stop 8 to 75 regulate the angular position of the collar. Fixed as by welding to the plate A adjacent one side of the slots 11, 18 and 24 are strips 27, 28 and 29 respectively of brass or other suitable material which are provided with a 80 number of serrations or teeth 30 the points of which are substantially flush with the sides of the slots.

In practice each operator will be given a 85 chart containing a list of the different styles together with the proper adjustment for each style. The adjustment may read D—4½, L—5, S—8 in which event the plate 5 will be moved to a position four and one-half teeth from the right end of the series 90 of teeth 30, the arm 9 will be moved to a position five teeth from the upper end of the series of teeth in strip 28, and the stop 8 will be moved to a position eight teeth from the right-hand end of the series in strip 29. 95 In this manner each operator may adjust his machine without calling upon an expert gauge setter.

Numerous changes in details of construction and arrangement may be effected without departing from the spirit of the invention especially as defined by the appended claims and although the invention has been described in connection with a button hole machine it is to be understood that it is not limited exclusively thereto but may be embodied in other machines requiring careful adjustment and positioning of parts.

I claim:

1. A device for holding collars on a button-hole machine having a stitching and cutting mechanism, said device comprising a plate with an opening which is adapted to be permanently located beneath said stitching and cutting mechanism, a stop disposed in said opening and movable to substantially any adjusted position within a certain area and being adapted to engage a certain part of a collar to locate it accurately in said area, a second stop spaced from the opening and supported upon the plate, said second named stop being adjustable solely along a path defined by a single line and being adapted to engage a portion of the collar to adjust it angularly in relation to the first named stop.

2. A device for holding collars on a button-hole machine having a stitching and cutting mechanism, said device comprising a plate having an intermediate opening

adapted to be permanently located beneath said stitching and cutting mechanism, a stop disposed in said opening and adapted to engage a portion of a collar, and means for adjustably supporting said stop in relation to said plate comprising an L-shaped member having one of its legs slidably

mounted along one side of the plate, an arm having one end adjustably mounted for movement along the other leg and supporting the stop adjacent its opposite end. **10**

Signed by me at Troy, New York, this 231d day of October, 1924.

HARRY D. SIMMONS.
